UNITED STATES PATENT OFFICE.

JOHN W. IPPERS, OF NEW YORK, N. Y., ASSIGNOR OF ONE-HALF TO CARL A. ROESSEL,
OF BROOKLYN, NEW YORK.

MACHINE FOR MAKING METALLIC PRINTING-ROLLERS.

1,046,792.

Specification of Letters Patent.

Patented Dec. 10, 1912.

Application filed January 3, 1910, Serial No. 536,046. Renewed April 1, 1912. Serial No. 687,774.

To all whom it may concern:

Be it known that I, JOHN W. IPPERS, a citizen of the United States of America, residing in New York, in the borough of Brooklyn, county of Kings, and State of New York, have invented certain new and useful Improvements in Machines for Making Metallic Printing-Rollers, of which the following is a specification.

10 This invention relates to an improved machine for making metallic printing-rollers by which inked designs may be transferred by repeats from a transfer-surface to a printing-roller without distorting or squashing the design.

15 The invention consists of a machine for making metallic printing-rollers which comprises a transfer-roller adapted to be inked with the desired design, a printing-roller 20 adapted to receive said design, gearing between the shafts of said rollers for rotating them in contact with each other for transferring the design to the printing-roller, means for separating said rollers as soon as 25 the design is transferred, and means for longitudinally moving the transfer-roller to a point adjacent to the first transfer-design for repeating the design on the printing-roller.

30 The invention consists further of indicating means in connection with the transfer-roller and the carriage supporting the same for correctly registering the design on the transfer-roller in relation to the printing- 35 roller so as to repeat the same, and the invention consists lastly of certain additional features of construction which will be fully described hereinafter and finally pointed out in the claims.

40 In the accompanying drawings, Figure 1 represents a front-elevation of my improved machine for making metallic printing-rollers, Fig. 2 is a rear-elevation of the same, partly in section through the supporting- 45 standards of the machine, Fig. 3 is a vertical transverse section on line 3, 3, Fig. 1, drawn on a larger scale, and Figs. 4 and 5 are respectively a side-elevation of the transfer-roller and a vertical transverse section of the 50 same on line 5, 5, Fig. 4, drawn on a still larger scale.

Similar reference characters indicate corresponding parts throughout the different figures.

In applying a design to a copper printing-roller, which is to be used in printing textile fabric, wall-paper and the like, it has been customary heretofore to engrave the design by hand on the printing-roller or to transfer it to the roller by the use of transfer-paper. 55 These processes are expensive and open to many objections. By the improved machine delicate designs can be transferred from a hard-surface transfer-roller to a printing-roller and repeated on the same until the 60 surface of the printing-roller is completely covered with repeated designs. In order to accomplish this result, the surface of the transfer-roller, which is preferably of zinc, and the surface of the printing-roller, which 65 is preferably of copper, are smoothened and polished and then etched over the surfaces which are to receive the ink of the design. This etching may be done, for example, by a solution of one ounce of nitric acid, twelve 70 ounces of water and two ounces of alum powder, for about two minutes, so that a smooth but finely-grained surface is imparted to the surfaces of the two rollers. The 75 design is applied to the zinc transfer-roller in any ordinary way, either by use of ordinary transfer-paper, as is well known in the art, or by a flexible transfer-plate secured to the transfer-roller, after which the ink of the design is converted into a solid resist and 80 the portions which are unprotected are then etched, so as to leave the design in relief. The design on the transfer-roller is then 85 suitably inked and the roller rolled in contact with the copper printing-roller, whereby the design is transferred to the printing-roller, without distortion or squashing of the ink.

Referring to the drawings, the frame of the machine consists of a base 1 and upright side-standards 2. In recesses at the upper part of the side-standards 2 are guided journal-bearings 3 which support the shaft 5 of the printing-roller 10. The shaft 5 is provided at one end with a gear-wheel 6 which receives motion from a pinion 4 on a short shaft 7 provided with a hand-wheel 8, the shaft 7 being supported in bearings 9 on the right-hand standard 2. Above the journal-bearings 3 of the shaft 5 are arranged on the side-standards vertically-adjustable followers 11, between which and the journal-bearings are interposed blocks 105

12 of felt or other flexible material, said followers being provided with screw-spindles 13 which turn in threaded perforations of inverted U-shaped frames or yokes 14 that are releasably supported on the upper ends of the side-standards, as shown in Fig. 3. The screw-spindles 13 of the followers 11 are provided with hand-wheels at their upper ends so as to permit the raising or lowering of the followers when it is desired to remove the shaft 5 of the printing-roller or replacing it, after which the followers are lowered on the yielding blocks for pressing them onto the upper portions of the journal-bearings. The yielding blocks 12 of felt or other material serve for the purpose of permitting the printing-roller to yield when pressure is exerted on the same.

In the side-standards 2 are further arranged below the journal-bearings 3, bracket-bearings 15 for holding a second shaft 16, which is provided with gear-wheels 18 that mesh with gear-wheels 17 on the shaft of the printing-roller 10. The gears 17 and 18 are so proportioned to the relative diameters of the printing and transfer-rollers that upon the rotation of the shaft of the transfer-roller the travel of the same will be equal to the surface-travel of the printing-roller. The transfer-roller 20 is rotated by the gear-wheels 17 and 18 from the short shaft and the printing-roller, it being splined to its shaft so as to be capable of longitudinal movement thereon. Alongside of the gears 17 and 18 are arranged plain rollers 21 and 22, which are equal in diameter with the gears 17 and 18, and which rotate one in contact with the other. The rollers 22 are provided in line with the edge of the design on the transfer-roller with raised portions 23 which enter under the rollers 21 on the shaft of the printing-roller and serve to lift the latter out of contact with the transfer-roller at the moment when the entire design is transferred to the surface of the printing-roller. By this arrangement the design is accurately transferred to the surface of the printing-roller and a reliable matching at the edges produced, the printing-roller being held in raised position by the raised portions 23 and out of contact with the transfer-roller. The yielding cushioning blocks 12 "give" sufficiently for permitting this lifting motion of the shaft of the printing-roller.

The transfer-roller is supported on a carriage 25, which is moved along guideways 26 on a horizontal platform 27 supported by the side-standards 2. The carriage 25 has uprights 29 the upper ends of which engage flanged sleeves 30 which are located adjacent to the ends of the transfer-roller 20 and which shift the latter along with the carriage when the same is moved in one

direction or the other over the platform 27. Threaded sockets 31 are supported on the rear-uprights 29 and engaged by a screw-spindle 32 which turns in bearings 33 of the side-standards 2, and which is rotated by a hand-wheel 34, so that the carriage 25 and the transfer-roller 20 can be shifted on the platform 27 to any desired point. A pointer 35 on the rear-upright 29 and a horizontal scale 36 serve for accurately registering the position of the transfer-roller in its various positions lengthwise of the printing-roller. A graduated disk 38 on the left-hand standard 2 and an indicator 37 on the hub of the hand-wheel 34 serve to adjust the final position of the transfer-roller and the design on the same relatively to the circumference of the printing-roller.

The threaded sockets 31 are split, that is to say, made of two semi-sections which are supported on vertically-sliding bracket-plates 40 that are guided on the rear-uprights 29 and are provided with horizontal slots engaged by pins 42 on a centrally pivoted disk 41 mounted on each rear-upright 29, said disks having handles 43, so that on turning the disks, the split and inferiorly-threaded socket-sections clear the screw-spindle and permit thereby the easy and convenient shifting of the carriage and the transfer-roller in longitudinal direction in the guideways of the platform, so that the transfer-roller can be placed into the required position relatively to the printing-roller, after which the socket-sections are returned by the disks into engagement with the screw-spindle.

At the lower parts of the side-standards is supported, below the platform, a shaft 50 which is held in position against longitudinal displacement by collars 51 bearing against the inner faces of the standards, and which is provided at its outer ends with bevel gear-wheels 52 that mesh with bevel gear-wheels 53, of equal size, placed on the lower threaded ends of vertical shafts 54. To one end of the shaft 50 is applied a hand-wheel 55 for turning the shaft 50. The inferiorly-threaded hubs of the horizontal bevel gear-wheels 53 are applied to the lower threaded ends of the upright shafts 54 that are guided in corresponding holes in the side-standards, so as to produce by the turning of the shaft 50, the raising or lowering of the upright shafts 54 according to the direction in which the governing shaft 50 is turned. The upper ends of the upright shafts 54 engage recesses in the lower ends of the guide-blocks 3 of the shaft 5 of the printing-roller and permit thereby the lifting or lowering of the same out of or into contact with the surface of the transfer-roller. The raising of the shaft of the printing-roller permits the direct adjustment of the carriage of the transfer-roller

so as to place the latter into the required position for transferring the design to the printing-roller.

The transfer-roller 20 shown in detail in Figs. 4 and 5. It is provided with a shouldered ledge 45 which is attached by screws 46 to the transfer-roller, said ledge being provided with screws 47 for clamping one end of a flexible transfer-plate having the design to be repeated on its surface. Adjacent to the ledge 45 is arranged a split clamping-roller 48 into which the opposite end of the transfer-plate is inserted and then clamped thereto by its screws. The clamping-roller 48 is then turned slightly on its axis, so that the transfer-plate is tightly stretched around the circumference of the printing-roller and retained in this position by means of spring-pawls 49, which engage teeth 43 adjacent to each end of the clamping-roller 48. The spring-pawls 49 are released from the teeth 43 when it is desired to remove the transfer-plate and replace a new one into position on the transfer-roller.

The operation of my improved machine for making metallic printing-rollers is as follows: The carriage on which the transfer-roller is supported is moved by the screw-spindle to one end of the machine so as not to come in contact with the printing-roller. A flexible transfer-plate, the design of which is properly inked with transfer-ink, is then mounted on the transfer-roller by inserting and clamping one edge in the ledge 45 and passed around the transfer-roller, and then attaching its opposite end in the split clamping-roller, the plate being then tightly clamped by the screws 49 of the clamping-roller. The clamping-roller is then turned on its axis so as to stretch the yielding transfer-plate around the transfer-roller, as shown in Figs. 4 and 5. Simultaneously the spring-actuated pawls engage the teeth at both ends of the clamping-roller. The transfer-roller is then placed into contact with the printing-roller, which is then turned until it is lifted by the raised portions on the lower contact-rollers so as to be moved out of contact with the transfer-plate. The transfer-roller is then moved forward by its screw-spindle until the transfer-plate is below the adjacent portion of the printing-roller. The transfer-roller is then turned on its axis into its former position and the surface of the transfer-plate inked in again. The printing-roller is then lowered again so that the transfer-plate is placed in contact with the printing-roller. The hand-wheel of the shaft of the printing-roller is then turned, so that the inked design on the surface of the transfer-plate is transferred to the printing-roller, forming the first repeat on the same. The shifting motion of the

transfer-roller and its carriage is indicated by the pointer 35 on the scale 36. After the transfer is made, the printing-roller is again raised automatically out of contact with the transfer-roller, the transfer-plate inked in again and the transfer-roller moved forward by its screw-spindle to the distance required so as to transfer a second repeat on the printing-roller, and so on. The extent of the axial return-motion of the transfer-roller is indicated by the indicator on the screw-spindle, and the longitudinal motion by the pointer on the movable carriage which is moved over the stationary scale. When all the repeats required by the width of the fabric to be printed are transferred to the printing-roller, so that it is entirely covered by the successively transferred "repeats," the printing-roller and its shaft are then removed from the machine by raising the followers, and the printing-roller is then slipped off from its shaft and a new printing-roller placed thereon. The unprotected portions of the printing-roller removed from the shaft are then etched away, after which the printing-roller is ready for printing on textile fabrics in the manner well known in the art.

Having thus described my invention, I claim as new and desire to secure by Letters Patent:

1. The combination of a transfer-roller adapted to be inked with the required design, a printing-roller adapted to receive the design, shafts supporting said rollers, intermeshing gears on said shafts, contacting-rollers at each end of each shaft, the rollers on one shaft having raised portions on the periphery, and means for rotating said shafts.

2. The combination of a transfer-roller adapted to be inked with the required design, a printing-roller adapted to receive said design, the printing-roller being longer than the transfer-roller, gear-wheels between said rollers for positively rotating them in contact with each other and at the same peripheral speed for transferring the design on the transfer-roller to the printing-roller, means for automatically separating said rollers from each other, a carriage for supporting said transfer-roller, means for shifting the carriage and transfer-roller in longitudinal direction, and indicating means for registering said transfer-roller with relation to the design previously transferred to said printing-roller.

3. The combination of a supporting-frame, a transfer-roller, a printing-roller above the same, means for imparting simultaneous rotary motion to the printing and transfer rollers, a carriage engaging the transfer-roller, means for moving the carriage and transfer-roller lengthwise of

the printing-roller, indicating means for placing the transfer-roller into proper position relatively to the printing-roller, means for lowering or raising the printing-roller into or out of contact with the transfer-roller, and means for automatically raising the printing-roller out of contact with the transfer-roller when the inked design thereon is transferred to the printing-roller.

10. 4. The combination of a transfer-roller, a printing-roller, shafts for said rollers, means for constraining said rollers to rotate with equal peripheral speed, and pairs of co-operating rollers mounted on said shafts respectively beyond the ends of said rollers, one roller of each pair having a raised portion on its periphery.

5. The combination of a printing-roller, a longitudinally movable transfer-roller, a longitudinally immovable shaft for said transfer-roller, means for constraining said rollers to rotate with equal peripheral speed, means for at will causing both ends of said printing-roller to be simultaneously raised, 25 additional means for automatically raising said printing-roller, a carriage engaging said transfer-roller, a split screw-socket car-

ried by the carriage, a screw-spindle engaged by said socket for shifting the carriage lengthwise of the machine, means for releasing said split socket, an indicating-finger carried by said spindle, and a stationary graduated disk for said finger.

6. The combination, with the side-standards of a supporting-frame, of a printing-roller the shaft of which is supported in journal-bearings in said side-standards, a transfer-roller below the printing-roller, gear-wheels for imparting simultaneous rotary motion to the printing and transfer rollers, adjustable followers above the journal-bearings of the shaft of the printing-roller, cushioning blocks interposed between said journal-bearings, and followers, and means for automatically raising the printing-roller after each rotation of the printing and transfer rollers.

In testimony, that I claim the foregoing as my invention, I have signed my name in presence of two subscribing witnesses.

JOHN W. IPPERS.
